UNITED STATES PATENT OFFICE.

ARTHUR LIPSCHUTZ AND MAX TOLTZ, OF ST. PAUL, MINNESOTA.

TRAIN-LIGHTING APPARATUS FOR COMPRESSED ACETYLENE GAS.

SPECIFICATION forming part of Letters Patent No. 633,866, dated September 26, 1899.

Application filed August 3, 1899. Serial No. 725,857. (No model.)

To all whom it may concern:

Be it known that we, ARTHUR LIPSCHUTZ and MAX TOLTZ, of St. Paul, Ramsey county, Minnesota, have invented certain new and useful Improvements in Train-Lighting Apparatus for Compressed Acetylene Gas, of which the following is a specification.

The invention relates to improvements in lighting systems for railway-trains; and the object of the invention is to provide means whereby acetylene gas under high pressure can be carried within a suitable receptacle in or under a passenger-coach or other railway-car with absolute safety.

15 The invention consists generally in providing a reservoir or tank covered with a suitable non-conductor of heat, leaving its seams or joints exposed, but made tight by a material or substance that will fuse at a comparatively low temperature and permit the contents of the tank to escape and prevent an explosion of the gases therein should the tank be subjected to an intense heat, as by the burning of the car or train.

25 Further, the invention consists in providing a high-pressure pipe composed of material fusible at a comparatively low temperature leading from a high-pressure tank, or in providing the high-pressure pipe having its 30 seams filled with a substance adapted to fuse at a comparatively low temperature and said pipe being covered, except over its seams, by a suitable non-conductor of heat.

Further, the invention consists in providing 35 a relief-valve in said tank and means for automatically opening said valve when the temperature outside the tank has reached a certain predetermined point.

Further, the invention consists in various 40 constructions and combinations, all as hereinafter described, and particularly pointed out in the claims.

In the accompanying drawings, forming 45 part of this specification, Figure 1 is a side elevation of one end of a railway-coach with my invention attached thereto. Fig. 2 is a longitudinal section of the gas-tanks, showing the connections leading to the service-pipe. Fig. 3 is a transverse section on the line $x-x$ 50 of Fig. 2. Fig. 4 is a detail of the relief-valve and its connections. Fig. 5 is a section on the line $y-y$ of Fig. 4. Fig. 6 is a cross-section of a steel high-pressure pipe having a

soldered horizontal seam. Fig. 7 is a cross-section of a tin pipe capable of withstanding 55 high pressure.

In the drawings, 2 represents the coach and 3 the tank, preferably cylindrically in form, its main portion being formed, preferably, of a single steel plate having its edges overlapping to form a longitudinal joint or seam, said edges being secured together by rivets or bolts and the seam being made tight against the high pressure of gas by a quantity of soft solder 4, placed between the overlapping edges 60 of the plate and around the bolts or rivets therein. The heads or ends 5 preferably bulge outwardly and are securely riveted or bolted to the ends of the tank, the joints between the same being filled with solder in the same 70 manner as described with reference to the longitudinal joint. The body of the tank and the heads or ends are covered with a suitable non-conductor of heat, such as layers of asbestos 6 and 7, leaving the seams or joints exposed, so 75 that the solder therein will be more quickly affected by heat outside the tank, and one of the heads 5 has a nipple 8 to receive the threaded end of a pipe 9, to which a supply-valve 10 and a pressure-gage 11 are connected. 80 The pipe 9 we designate as the "high-pressure" pipe, either made of tin and fusible at a comparatively low temperature, but sufficiently strong to withstand the desired pressure, or of steel having longitudinally-overlapping seams filled with soft solder or other 85 suitable substance in the manner heretofore described and covered, except over its seams, with layers of asbestos or other non-conductor of heat.

90 The high-pressure pipe 9 and the filling or supply valve 10 are adapted to fuse or leak at a temperature of about 500° Fahrenheit, and we regard the high-pressure pipe constructed in the manner heretofore described as one of 95 the most essential features of our invention, for should an ordinary gas-pipe be used between the train-service pipe and the high-pressure tank and a fire start near the pipe and at a considerable distance from the tank 100 the gas in the tank might become heated sufficiently to cause an explosion before the temperature outside the tank reached the fusing-point of the substance in the seams thereof. By providing a high-pressure pipe of material 105 fusible at a comparatively low temperature

or having its seams filled with a substance such as soft solder all danger of gas explosion in the tank from a fire at a distance therefrom and near the high-pressure pipe is avoided.

As a further safeguard against explosion of the gas within the tank, we prefer to provide a relief-valve in connection therewith, which consists in providing a threaded plug 14 within an opening in the wall of the tank, said plug having a central opening 15 and a valve-seat 16 to receive a disk 17, held thereon by the pressure of gas within the tank and pivotally connected to a lever 18, that extends through said opening 15 and is in turn pivotally supported on a lug 19, provided on said plug, as shown in Fig. 4. The lever 18 is provided with an arm 20, fitting within a slot or opening in the end of the bar 21, said bar being composed of zinc or similar substance quickly affected by changes of temperature, secured at one end of said tank, preferably directly beneath the car-body, by screws or bolts and at its other end held in position by a guide 22.

Acetylene gas under pressure will not explode from sudden shock or continued vibration, but will become disassociated at a temperature of about 1,432° Fahrenheit, followed by a great increase of pressure and consequent explosion. This fact has rendered the use of acetylene gas dangerous, especially in connection with railway-trains, where a fire, as in a burning wreck, might cause the explosion of a number of tanks and a great loss of life and destruction of property. In the event of the coach taking fire after a wreck or from other causes the temperature around the gas-tank and the high-pressure pipe will soon be raised, and when it reaches about 400° Fahrenheit either the solder in the seams of the tank or the high-pressure pipe or the material of which the high-pressure pipe is composed will fuse sufficiently to cause a leak and permit the escape of the gas from the tank before the temperature has reached the danger-point or before the gas has been heated sufficiently to cause its disassociation. At the same time the zinc bar 21, being preferably directly beneath and near the car-body, will quickly become heated and, expanding longitudinally, will open the relief-valve and permit the gas to escape from the tank.

We do not wish to be confined to the use of the particular material shown and described herein for rendering the seams of the tank or the high-pressure pipe fusible at a certain predetermined temperature, as any other substance fusible at a comparatively low temperature may be used, nor do we wish to be confined to the particular means shown for connecting the gas-tank to the train-service pipe, nor to the particular construction of the relief-valve, as various modifications of the same may be made without departing from our invention.

Having thus described our invention, we claim as new and desire to secure by Letters Patent—

1. A reservoir or tank for compressed acetylene gas covered, except over its seams, with a suitable non-conductor of heat, and said seams being filled with a material which when subjected to heat will fuse and permit the escape of gas before its point of disassociation has been reached. 70
2. A reservoir or tank for compressed acetylene gas covered, except over its seams, with a suitable non-conductor of heat, said seams being filled with material adapted to fuse at a comparatively low temperature and permit the escape of gas from the tank, a relief-valve provided in said tank, and means for automatically opening said valve when the temperature outside the tank has reached a certain predetermined point, substantially as described. 80
3. A train - lighting apparatus for compressed acetylene gas, comprising a reservoir or tank having its seams filled with a material adapted to fuse at a comparatively low temperature, a high-pressure pipe leading from said tank and also fusible at a comparatively low temperature, a reducing-valve, a low-pressure or train-service pipe leading therefrom, and suitable gas-burners provided in said service-pipe. 90
4. A train - lighting apparatus for compressed acetylene gas, comprising a reservoir or tank covered, except over its seams, with a suitable non-conductor of heat, said seams being filled with a material adapted to fuse and leak at a comparatively low temperature, a high-pressure pipe also adapted to fuse or leak at a comparatively low temperature, a reducing-valve, a low-pressure service-pipe leading therefrom, and suitable gas jets or burners provided in said service-pipe. 95
5. A train - lighting apparatus for compressed acetylene gas, comprising a reservoir or tank covered, except over its seams, with a suitable non-conductor of heat and having its seams filled with material fusible at a comparatively low temperature, a relief-valve provided in said reservoir, means for automatically opening said valve when the temperature outside the reservoir has reached a certain predetermined point, a high-pressure pipe leading from said reservoir, and fusible at a comparatively low temperature, a reducing-valve, a low-pressure service-pipe connected therewith, and gas jets or burners provided in said service-pipe, substantially as described. 105

In witness whereof we have hereunto set our hands this 31st day of July, 1899.

ARTHUR LIPSCHUTZ.
MAX TOLTZ.
